By His Attorney:-

UNITED STATES PATENT OFFICE

JOHN BRANDWOOD, OF BIRKDALE, SOUTHPORT, ENGLAND

PRODUCTION OF ARTIFICIAL SILK THREADS

Application filed April 21, 1930, Serial No. 446,031, and in Great Britain November 6, 1929.

The invention relates to the production of artificial silk threads and more specifically to that system of production wherein the threads are wound upon a spool or bobbin 5 in a bobbin winding frame and then passed to a mechanical twisting device which imparts the twist to the threads.

In a usual extrusion process, spinning and winding take place on a small bobbin in the 10 spinning machine, and the threads during subsequent twisting are drawn over the end of the bobbin—the latter being suitably held—and over a rotating winding drum on to the twisting device which may be a cap 15 spinning device. This is disadvantageous as friction on the threads is always present.

The present invention has for an object a 20 means for producing a twisted thread by which means the friction to which I have referred may be eliminated and the use of a 25 winding drum altogether avoided. A further object of the invention is to make possible an increase in the production of a spinning machine. With these objects in view 30 and according to my invention the threads are wound upon a spool of large diameter as compared with the radial thickness of thread mass which may be wound upon it, the threads being then drawn off under tension 35 to a thread twisting device while a positive rotation is imparted to the spool, the said threads leaving the spool transversely thereof. To apply tension the peripheral speed at which the large spool is rotated may 40 be regulated in relation to the speed of draw-off by the twisting device, to give a desired tension. The threads thus leave the large spool coil by coil exactly as they were wound on, and not over the spool end, as heretofore.

The provision of a large spool as aforesaid and the drawing of the threads therefrom in the manner in which they were wound on, that is to say transversely of the spool 45 length, gives an even and regular delivery with desired tension, and eliminates friction.

A conspicuous advantage of the use of a large spool is that such spool may itself be employed in the bobbin spinning frame, instead of the usual small spool. The large

spool being cross wound in such machine it is sufficient to take it from the machine, mount it as before described, and proceed to cap twisting. I find by experiment that a spool of say six inches diameter on the 55 barrel can be wound with a thickness of about five-eighths of an inch of threads evenly and without difficulty, thus considerably increasing the spinning frame production by 60 greatly lessening the dosing periods, and 65 eliminating the handling of large quantities of small spools.

The large spool may be foraminous so that any desired fluid treatment may be carried out upon the threads wound thereon, 65 before twisting takes place.

The means for rotating the large spool may be any convenient and, if desired, known "compensator" means may be employed to vary the rotational speed to keep 70 the peripheral speed constant as the diameter of wound thread decreases due to unwinding. With a spool of large diameter of barrel as before described however the peripheral speed variation during the whole of 75 the unwinding is negligible, and does not affect the ultimate twist.

A convenient and simple form of apparatus for the purpose of performing the invention is illustrated in the annexed diagrammatic drawing, which is a side elevation of a spool in position with its rotating means and showing the passage of the threads from the spool to a twisting device.

The spool 1 is of large diameter on the 85 barrel thereof as shown, and has flanges 2, the threads wound thereon being designated by α in the drawing. A turntable 3 which may be of wood or may be of metal provided with a friction surface, for instance ebonite 90 or wood, is rotatably mounted in a bar 4 extending the length of the twisting frame, and bears at the lower extremity of its shaft 5 a friction disc 6 which is in frictional contact with a further disc 7 mounted on a shaft 95 8, which shaft is rotated by gearing at the end of the twisting frame. There may be any desired number of twisting heads on the frame, each mounted as shown to receive a spool, and all of them driven from discs such 100

as 7 fixed on shaft 8 which extends the length of the frame.

From spool 1 the thread α passes through a guide 9 and thence to thread guide 10 and from the latter proceeds to a cap twisting device of known character shown at 11, being wound on a bobbin or pirn 12.

Each cap spindle of a frame may be driven by a band or tape from a tin drum or the like as usual in yarn spinning frames. The fact that the spool 1 is merely placed in position on the turntable 3 allows of easy removal of the said spool when empty and its replacement by a full one, and further, it will yield to any incidental and undesired pull upon the thread passing through the guides 9 and 10.

I claim:—

1. For the twisting of artificial silk threads as received from the spinning nozzles of a spinning machine, a spool on which the threads may be wound, such spool having a large diameter as compared to the radial thread thickness which may be wound thereon, means for mounting the spool and for imparting a thread "let-off" rotation thereto around its longitudinal axis, and a positively operated twisting and winding device adjacent to the rotated spool position.

2. For the twisting of artificial silk threads as received from the spinning nozzles of a spinning machine, a spool on which the threads may be wound, such spool having a large diameter as compared to the radial thread thickness which may be wound thereon, a turntable on which the spool may be vertically disposed, means for rotating such turntable, and a positively operated twisting and winding device adjacent to such turntable.

3. For the twisting of artificial silk threads as received from the spinning nozzles of a spinning machine, a spool on which the threads may be wound, such spool having a large diameter as compared to the radial thread thickness which may be wound thereon, means for mounting the spool and for imparting a thread "let-off" rotation thereto around its longitudinal axis, and a positively operated cap twisting device adjacent to the rotated spool position.

4. For the twisting of artificial silk threads as received from the spinning nozzles of a spinning machine, a spool on which the threads may be wound, such spool having a large diameter as compared to the radial thread thickness which may be wound thereon, a turntable on which the spool may be vertically disposed, means for rotating such turntable, and a positively operated cap twisting device adjacent to such turntable.
